UNITED STATES PATENT OFFICE.

CLAIR D. LAKE, OF BINGHAMTON, NEW YORK, ASSIGNOR TO THE TABULATING MACHINE COMPANY, OF ENDICOTT, NEW YORK, A CORPORATION OF NEW JERSEY.

HAMMER CONTROL FOR TABULATING MACHINES.

Application filed March 6, 1922. Serial No. 541,437.

To all whom it may concern:

Be it known that I, CLAIR D. LAKE, a citizen of the United States of America, residing at Binghamton, in the county of Broome and State of New York, have invented certain new and useful Improvements in Hammer Controls for Tabulating Machines, of which the following is a full, clear, and exact description.

10 In printing tabulators of the general type shown in my prior Patent No. 1,379,268, a plurality of type carriers are provided, each of which is provided with a slidable type bar. The printing operation is effected by 15 a plurality of hammers which are simultaneously swung so as to react upon the type or upon blank points upon the type carriers. The type thus struck strikes a type ribbon and print proper characters upon a record 20 sheet.

With devices of this sort it is desirable to provide means for controlling the action of combinations of the hammers so as to suppress the printing of characters at selected 25 points upon the sheet. The present invention is directed to the provision of a hammer control of this character which may be selectively adjusted to render one or more type hammers inefficient.

30 In the drawings,

Fig. 1 shows a vertical sectional view of a tabulator embodying my improvements.

Fig. 2 shows a detail top view of one 35 group of hammer locks and their associated parts.

Fig. 3 is a detail side view of the same parts.

Referring to Fig. 1, 10 represents one of the type carriers. These carriers are slotted to receive individually slidable type 40 11 and the carriers are differentially displaced at each operation by the means described in my prior patent. To effect the printing, a plurality of pivotally mounted hammers 12 are provided. These hammers are normally 45 spring retracted by springs 13 and are swung into contact with the type by means of a bail 14. Bail 14 is pivotally mounted upon a shaft 15 and is normally impelled to 50 move to the position shown in Fig. 1 by means of a spring 16. Movement of the bail counter clockwise is limited by a stop.

17 against which depending finger portions 18 abut.

During a printing operation, pawl devices 55 19 are carried bodily upward causing shouldered portions thereon to contact with the sleeved shaft 17 so as to cause the pawls to be rocked counterclockwise and into engagement with the depending fingers 18. 60 Further movement of the parts causes the bail 14 to be rocked clockwise and allows the hammer 12 to be swung away from the type under the pull of springs 13. Continued and further counterclockwise rocking 65 of the pawls 19 causes the latter to trip off from engagement with the fingers 18. The bail 14 then swings under the power of spring 16 against the hammers 12 impelling 70 the same against the type 11.

In order to selectively suppress the action of one or more of the hammers, provision is made for swinging the hammers slightly forward out of their normal position so that bail 14 upon its striking movement does not 75 react thereon. Preferably the hammer controls comprise a series of finger members 20 arranged in groups and pivotally mounted upon a shaft 21. The shaft 21 is mounted in bracket 24 which is secured to frame 80 member 23. The finger members 20 are provided with shouldered portions 22 and 25 adapted to abut against or engage a frame member 23. By swinging these fingers 20 clockwise from the position marked A to the 85 B position the tips of the fingers will engage the backs of the hammers and swing the same forward to such position as not to receive the impact of bail 14. The shouldered abutments 22 limit the movement of the 90 fingers 20 in their non hammer engaging position, and the shoulder portion 25 is adapted to limit their movement in the opposite direction.

It will be understood that tabulating machines of the type herein mentioned usually comprise a plurality of type carriers arranged in groups. By selectively shifting the hammer controlling fingers from the A to the B position, the action of individual 100 type or complete groups of type may be suppressed as desired by the operator. The hammer controls herein described are simple in their use and inexpensive to manu-

facture. Furthermore, the use of unnecessary springs upon the members is avoided and the devices are retained in noneffective or hammer controlling position by gravity.

5 I claim:

1. In a tabulating machine, a plurality of type, and carriers therefor, a plurality of pivotally mounted hammers, an impacting means therefor, and means for selectively displacing one or more of the said hammers out of the path of said means when it is desired to suppress the printing from one or more type.
- 10 2. In a tabulating machine, a plurality of pivotally mounted type hammers, a plurality of type carriers and type carried thereby, a common actuating means for the type hammers, each of said hammers normally being in the path of said actuator, means for preventing printing by one or more of the type comprising means for suppressing the striking of one or more of the hammers by the actuator, said last mentioned means comprising a plurality of independently 25 movable members each having provisions for independently displacing a hammer out of the path of the actuating means.
- 30 3. In a tabulating machine, including type carriers, a plurality of type, a plurality of hammers therefor, means for suppressing the hammer action upon selected type comprising a plurality of pivoted fingers adapted to be displaced into or out of contact with said hammers, said fingers when in contact with the hammers becoming adapted to displace the latter out of cooperation with an operating member therefor.
- 35 40 4. A tabulating machine, a plurality of type hammers, a suppressing device for each of said hammers, an actuating means for said hammers, means dependent upon the

weight of said suppressing devices for retaining the same in non suppressing position relatively to said hammers.

45

5. In a tabulating machine, in combination with printing type and hammers therefor, individual suppressing devices for preventing effective actuation of said hammers, said individual devices each comprising a pivotally mounted individually adjustable finger, means for retaining one or more of said fingers in suppressing relation to the hammers, a common frame member adjacent said fingers, and shoulders on each finger adapted to engage the said frame when an individual finger is swung back from co-operation with its hammer.

55

6. In a tabulating machine in combination with a plurality of type and type carriers, a plurality of hammers, one for each type carrier, an actuating means having a determined amount of travel to impact against said hammers and cause the same to react upon the type, a plurality of pivot- 60 ed fingers shiftable into or out of contact with the said hammers, said fingers when in contact with said hammers being adapted to swing the same out of the path of travel of the actuating means and thereby suppress 65 the operation of certain type.

60

7. In a printing apparatus comprising a plurality of type carriers and type therein, a plurality of hammers for individually striking said type, a common actuator for all said 75 hammers to impel the same against the type, and means for individually displacing one or more of said hammers out of the path of said actuator whereby the movement of any one or more of the hammers may be suppressed.

80

In testimony whereof I hereto affix my signature.

CLAIR D. LAKE.
